UNITED STATES PATENT OFFICE.

WILLIAM JOHNSTON, OF LA JUNTA, COLORADO.

INJECTOR.

SPECIFICATION forming part of Letters Patent No. 315,630, dated April 14, 1885.

Application filed October 15, 1884. (Model.)

To all whom it may concern:

Be it known that I, WILLIAM JOHNSTON, of La Junta, in the county of Bent and State of Colorado, have invented certain new and useful Improvements in Injectors; and I do hereby declare the following to be a full, clear, and exact description of the invention, such as will enable others skilled in the art to which it appertains to make and use the same.

10 My invention relates to an improvement in injectors. Injectors used on locomotives, or wherever they are subjected to a constant jar, become after a short time more or less worn at the point where the sections come in contact. This wear will render the injector less and less effective, until it is necessarily cast aside as useless and a new one substituted. It is found, also, that by increasing the annular space between the intermediate and combining tube the work of the injector is materially increased.

15 My present invention has particular reference to that form of injector in which an intermediate tube is interposed between the receiving and combining tubes, of which the Friedmann injector is a type, although my invention, in one respect at least, applies equally to all forms of injectors in which two separate sections rest in contact with each other.

20 The object of my invention is to provide removable bearings adapted to take the wear between two sections, a further object being to provide removable bearings which shall at the same time form spacing-lugs, whereby the work of the injector is materially increased.

25 With these ends in view my invention consists in certain features of construction and combinations of parts, as will be hereinafter described, and pointed out in the claims.

30 In the accompanying drawings, Figure 1 is a longitudinal section of my improved injector, and Fig. 2 a view of the intermediate section in perspective.

35 A represents a steam-supply pipe leading from the boiler to the receiving-tube *a*.

40 B represents a water-supply pipe leading from a tank of water to the chamber *b* about the nozzle of the receiving-tube *a*. The chamber *b* is inclosed by a cylinder or barrel, *C*, in 45 one end of which the receiving-tube *a* is snugly fitted. An intermediate tube, *D*, is provided with a bell or funnel shaped mouth, *d*, the rim

of which fits the bore of the barrel *C*. The small end of tube *a* projects centrally into the funnel-mouth of the tube *D*, and is held in 55 the proper position therein by means of radial lips *E*, formed on the tube *a*, the said lugs resting in contact with the edge of the rim of the mouth *d*, and the ends of the lugs bearing against the inner surface of the barrel. The 60 nozzle of the intermediate tube, *D*, is provided with a series of ribs, *e*, preferably four in number, which extend longitudinally from an annular shoulder, *F*, adjacent to the rim at the funnel-mouth end of the tube to a point a short 65 distance back from the end of the nozzle. As hitherto constructed, the ends of the ribs *e* form rests upon which the edge of the funnel-shaped mouth *g* of the combining-tube *G* were adapted to rest.

70 My improvement consists in providing the ends of the ribs *e* with removable bearings *H*. These bearings *H* may be made of soft or hard metal, or of any material which it is found advantageous to use. They may be simply set in 75 sockets in the ends of the ribs, or may be screwed into threaded perforations made in the ends. They are preferably round and provided with flat heads, which receive the edge of the mouth *g* thereon. The combining-tube *G* is also provided with longitudinal ribs *h*, corresponding with the ribs on the intermediate section just described, but having recesses *I*, centrally located and semicircular in shape. The combining-tube *G* is further provided with an annular flange, *i*, which is connected with a similar flange, *K*, on the delivery-tube *L* by the straps *k*. The tube *G* is also provided with a hole, *m*, a short distance back from the end of the nozzle. The intervening spaces between 80 the tube *D* and the barrel *C* are connected by the annular space about the funnel end of the tube *G*, and this same space is also connected with the overflow-pipe *N*.

85 The several supply and delivery pipes being provided with suitable valves, the operation of my improved injector is the same in general as those heretofore constructed. I find, however, that the increase of the space between the intermediate and the combining 90 tubes in the manner in which I have accomplished it will render the injector much more effective than those hitherto constructed, my tests having shown that the amount of water

supplied to the boiler with a given pressure of steam is, as nearly as I can estimate it with the facilities I have at hand, fully one-tenth greater than the amount supplied by the former construction; and, further, that the injector will operate under a much lower pressure of steam than hitherto required to render it operative. I have not at present satisfied myself as to the theory for this increase. It may be due to the forcing of the overflow-water which backs into the chamber about the intermediate tube, and is drawn from thence into the main jet; or it may be due to the relative position of the end of the nozzle of the intermediate tube to the combining-tube; or it may be due to some entirely different cause.

The constant jar to which the injector is subjected—on the railway-locomotive, for example—will cause wear on the bearings between the sections D and G, and when this wear amounts to enough to render the injector partially or quite inoperative the bearings H can be readily removed, new bearings substituted in their place, and the injector thus made as good as new at a very slight expense. This advantage, coupled with the increase in work done, is, as will be readily observed, of the highest importance.

Having fully described my invention, what I claim as new, and desire to secure by Letters Patent, is—

1. In an injector, the combination, with a combining-tube and intermediate tube, of removable bearings adapted to form a rest for the end of the combining-tube, substantially as set forth.

2. In an injector, the combination, with a combining-tube and an intermediate tube, of a set of removable bearings secured to shoulders on the intermediate tube, adapted to receive and take the wear of the combining-tube, substantially as set forth.

3. In an injector, a set of removable spacing-lugs interposed between the intermediate and combining tubes, whereby the work done by the injector is increased, substantially as set forth.

4. In an injector, a set of removable spacing-lugs interposed between the combining and intermediate tubes, said spacing-lugs forming bearings between said tubes, substantially as set forth.

In testimony whereof I have signed this specification in the presence of two subscribing witnesses.

WILM. JOHNSTON.
